UNITED STATES PATENT OFFICE.

CHARLES FREDERICK LAGANKE, OF CLEVELAND, OHIO, ASSIGNOR TO
ELLIOTT-FISHER COMPANY, OF NEW YORK, N. Y., A CORPORATION
OF DELAWARE.

COMBINED RECORDING AND CALCULATING MACHINE.

No. 820,861.

Specification of Letters Patent.

Patented May 15, 1906.

Application filed March 14, 1905. Serial No. 250,059.

To all whom it may concern:

Be it known that I, CHARLES FREDERICK LAGANKE, a citizen of the United States, residing at Cleveland, in the county of Cuyahoga and State of Ohio, have invented a new and useful Combined Recording and Calculating Machine, of which the following is a specification.

This invention relates to a combined recording and calculating machine, and more particularly to a type-writer equipped with a computing device operated by the numeral-keys to effect a computation embracing the numerical values represented by the printed digits.

The object of the invention is to produce a machine especially adapted for totalizing numbers arranged in a plurality of comparatively narrow parallel columns disposed in immediate juxtaposition.

It has been proposed to equip a type-writer with a plurality of computing devices for totalizing a plurality of parallel columns. This is a feasible arrangement, provided the columns are spaced apart sufficiently to accommodate between them the adjacent side walls of the register-casings, and provided, further, that the spaces appropriated on the work-sheet to the respective columns equal in width the series of number-wheels of the respective computing devices or registers, since it is evident that in printing outside of a column which is narrower than the register appropriated to it the register or computing device would be actuated and a false computation effected. It happens, however, that in various commercial lines there have been adopted standard forms in the filling out of which the conditions above recited cannot be complied with. One such form is illustrated in the drawings, (see Figure 6,) it being noted that at the right-hand side of the sheet are three comparatively narrow columns in immediate juxtaposition—that is to say, separated only by dividing-lines. It is necessary to totalize each of these columns, and it is also desirable to provide for totals having a greater number of denominational positions than can be printed in the columns.

To the attainment of these ends the present invention is primarily directed; but a subordinate feature thereof resides in a novel arrangement of resetting mechanism where-

by certain independent sets of number-wheels may be reset separately or simultaneously, as desired.

In the accompanying drawings, Fig. 1 is a plan view of an Elliott-Fisher type-writer equipped in accordance with my invention. Fig. 2 is a vertical section of the computing device with a portion of the actuating mechanism thereof shown in elevation. Fig. 3 is a front elevation of the computing device. Fig. 4 is a plan view of the computing device with the cover removed. Fig. 5 is a transverse section on the line 5 5 of Fig. 2. Fig. 6 is a plan view of a form with a portion of the computing device shown in plan to illustrate the relation of the computing device to the columns to be totalized, and Fig. 7 is a sectional elevation of the machine.

For the purposes of this disclosure I have utilized an Elliott-Fisher type-writer as the recording mechanism of my machine. This type-writer is exemplified in Patent No. 573,868 to R. J. Fisher and is of that type wherein the printing or recording mechanism is movable longitudinally and laterally of a flat platen to effect the line and letter spacing of the characters printed upon the work-sheet supported in a flat spread-out condition upon the platen. No effort will be made to describe the structure of the machine further than to say that it comprises a machine-frame 1, movable longitudinally of the flat platen (not shown) and supporting a carriage 2, intermittently movable transversely of the platen upon the machine-frame and controlled in its step-by-step advance by letter and numeral keys 3 and 4, which operate the printing or recording devices.

In rear of the machine-frame 1 a guide-bar 5 is supported parallel therewith by brackets 6. On the bar 5 is slidably supported a computing device or register-casing 7, designed to be shifted along the bar and secured in position for use with respect to columns located at any desired point on the work-sheet. Within the casing 7 are mounted a series of digit-carriers or number-wheels, the special arrangement of which will be hereinafter more particularly described. For the present it may be said that these wheels are mounted to rotate upon a common axis which is parallel with the travel of the carriage 2 and that they are disposed to be en-

gaged in succession by a master-wheel 8, mounted on the type-writer carriage 2 and designed to be rotated a different distance by each of the numeral-keys. The manner of effecting the operative connection between the master-wheel and the numeral-keys need not be described in detail, for the reason that the specific construction and arrangement of this connecting mechanism constitute no part of my present invention, although it is shown in Figs. 1, 2, and 7 to complete the disclosure.

The number-wheels 9 are divided into independent groups or sets *a*, *b*, and *c*, all mounted upon the same shaft 10, which extends transversely of the casing 7 and is journaled in the opposite side walls thereof, as best shown in Fig. 5. In the present embodiment of the invention each group or set includes six wheels, representing thousands, hundreds, tens, and units of dollars, tens of cents, and cents, the tens-of-cents wheel being of double width to accommodate the decimal-space. Obviously, however, the number of wheels comprising each set may be varied, as well as the number of sets in the casing, and the wheels instead of representing dollars and cents may have any other appropriate significance, it being immaterial whether the unit is expressive of value or quantity and it being equally immaterial whether or not one or more wheels are utilized for the computation of decimal fractions. Each of the several wheels, as shown in Fig. 2, has twenty peripheral teeth bearing upon their end faces two series of characters ranging from "0" to "9," and as the wheels are rotated by the master-wheel these digits or characters are exhibited in succession at a sight-opening 11 in the top wall of the casing 7. Associated with the number-wheels of each set or group is suitable carrying mechanism, whereby when a given wheel moves from "9" to "0" the adjacent wheel of higher order will be automatically advanced a single increment. The specific character of this carrying mechanism constitutes no part of my present invention; but in order that the operation may be understood the mechanism shown more particularly in Figs. 2 and 4 for effecting the carrying, or transfer will be briefly described.

In rear of the wall 7 is disposed a rod 12, upon which are mounted a series of transfer-levers 13, one of these levers being arranged opposite each of the wheels, with the exception of the wheel at the right-hand end of each set or group, for which wheels it is unnecessary to provide transfer-levers, since no carrying movement thereof is ever effected. Each transfer-lever is provided at its front end with a laterally-offset contact-plate 14, extended between a pair of number-wheels and arranged to be engaged by either of a pair of lugs or projections 15, extending lat-

erally from the number-wheel to the right—that is to say, the lugs 15, which engage the contact-plate 14 of a given transfer-lever 13, are carried by the number-wheel to the right of the wheel opposite which the transfer-lever is located. The projections 15 are located at diametrically opposite points of the wheel. A complete rotary movement of a number-wheel is the equivalent of twenty increments, an increment being a unit of movement represented by the distance between two teeth. When a number-wheel is moved nine increments from its normal or set position, the digit "9" on said wheel will be exhibited opposite the sight-opening 11 and one of the projections 15, carried by the wheel, will be in contact with the plate 14 on the transfer-lever. The next increment of movement of the wheel will cause the projection 15 to depress the plate 14, and thus swing down the front end of the transfer-lever. This movement of the lever is designed to impart a single increment of movement to the wheel opposite which it is located—that is to say, the wheel to the left of the one which positively swings the lever.

The connection between each transfer-lever and the wheel served or carried by it is established through the medium of a transfer-dog 16, pivotally mounted at the front end of the lever and designed to extend over and engage one of the peripheral teeth of the adjacent number-wheel. The transfer-dogs 16 are swung forwardly into operative relation with the teeth of the number-wheels by vibrators 17, having their front ends 18 disposed to be engaged and operated by a vibrator-actuator 19, movable with the carriage of the type-writing machine. These vibrators 17 are also utilized to lock the transfer-levers 13 in their normal elevated positions, each vibrator having at its upper end a lateral projection 20, normally engaging a notch 21 in the adjacent transfer-lever. When the vibrator is operated by the actuator 19, the projection 20 moves out of the notch 21, thus releasing the transfer-lever, and by the same movement swings the dog 16 over a tooth of the adjacent number-wheel. The lever may then be swung down, as heretofore described, to effect the carrying or transfer of movement from one wheel to another. Coöoperating with the number-wheels are a series of swinging locators 22, which insure the alignment of the digits at the sight-opening.

Above the transfer-levers 13 are a series of locking-levers 23, each having a weighted rear end 24 and a curved front end 25. The transfer-levers 13 normally engage the locking-levers in rear of the fulcrums of the latter, so that when a transfer-lever is operated to transfer motion from one wheel to another it simultaneously operates the adjacent locking-lever for the purpose of swinging the front end of the latter into locking engagement.

with the wheel to which motion is transmitted. Thus each wheel is locked as soon as it has been moved an increment by the carrying mechanism. All of the locking-levers of the two right-hand groups or sets of wheels *b* and *c* are cooperatively related in a manner which causes each lever when swung down to automatically effect a corresponding operation of all of the locking-levers to the left, this relation of the locking-levers being incidental to the utilization of a single resetting device or lever for both of these two otherwise independent groups or sets of number-wheels. Each of the levers for the two groups of wheels except the lever serving the wheel at the left-hand end of the set *b* (see Fig. 4) is provided with a laterally-disposed lug 26, which extends over the upper edge of the adjacent lever to the left. Thus when one of the locking-levers is moved to its locking position its lug 26 will depress the adjacent lever, which will in turn depress the next lever, and so on throughout the series. The several locking-levers of the wheels *a*—that is to say, of the left-hand group or set—are similarly equipped with projections 26.

In a multiple register or computing device of the character under consideration it is desirable to provide for the simultaneous resetting of certain of the sets or groups of wheels independently of the remaining wheels. The reasons for this arrangement are various. For instance, one of the columns of numbers may be devoted to gross business for a given period, while the other two columns may be devoted to different parts of individual orders—for instance, the cost and selling prices. In this event the group of wheels for totalizing the first column would not be reset until the end of the period covered by the various transactions, while the two groups of wheels serving the other columns would be reset after the recording of each order. Similarly one column might be utilized for the totalizing of the weight or value of a whole consignment, the other two columns being devoted to totalizing the gross and net weights of individual lots included in the consignment.

Very many other uses showing the utility of the resetting arrangement to be described might be detailed; but those given are thought to be amply sufficient for the present purpose.

The number-wheels of the groups or sets *b* and *c* are reset by a resetting-lever 27, common to both groups. The resetting-lever 27 is located at the right-hand side of the casing, is fulcrumed at 28, and is provided at its front end with a toothed segment 29. This segment meshes with a pinion 30, fixed to the shaft 10 adjacent to its right-hand end and provided to rotate said shaft when the rear end of the lever 27 is elevated. Fixed to the shaft 10 between the number-wheels are a series of resetting-cams 31, one of which is pro-

vided for each number-wheel and is formed with two diametrically opposed shoulders 32. When the shaft 10 is rotated by the resetting-lever 27, one of these shoulders of each resetting-cam engages a resetting-pawl 33, carried by the adjacent number-wheel to the right, and as the shaft continues to rotate with the cam and pawl in engagement the number-wheel will be reset at zero. The transfer-levers are returned to their normal positions by a rocker 34 common to all the transfer-levers serving the two groups of wheels *b* and *c* and operated by a slide 35, projecting through the front of the register-casing and operated by the carriage during the retraction thereof. This slide 35 is also connected to the lower end of a swinging arm 36, having a projection 37, upon which bears the front end of a latch-lever 38.

It will of course be understood that preparatory to resetting certain or all of the transfer and locking levers may occupy their depressed positions, and for this reason a locking-lever retractor 39 is mounted to swing from a shaft 40 and is provided with forwardly-extending arms 41 and 42, (see Fig. 4,) the latter having an angular end 43, which projects over the rear ends of one or two of the locking-levers at the left-hand end of the right-hand group—that is to say, the angular end 43 projects over the two locking-levers which serve the two wheels of highest order of the group *b*. The front end of the arm 41 of the retractor 39 is disposed under the lug or projection 37 of the swinging arm 36. Thus when the latch-lever 38 is swung preparatory to the resetting operation the projection 37 will be depressed, thus swinging the arm 36 to operate the rocker 34 and restore the transfer-levers 13 to their normal positions and also swinging the locking-lever retractor 39 to cause the arm 42 thereof to depress the rear ends of the locking-levers engaged thereby. The front ends of these levers are thus swung up, and this motion is communicated to the entire series of levers by reason of the fact that as each is elevated it strikes the lateral projection 26 of the adjacent lever of lower order and moves said lever with it. The wheels being thus released, the lever 27 is swung to reset the same.

Mechanism is also provided for restoring the transfer and locking levers to their normal positions at the end of the resetting operation; but it is thought to be unnecessary to describe this mechanism in detail.

The manner in which the two groups of wheels *b* and *c* are simultaneously reset has now been explained, and it may be remarked that the group or set of wheels engaged by *a* are reset by an independent mechanism. These latter wheels *a* instead of rotating directly on the shaft 10 are mounted on a sleeve 44, encircling a reduced portion 10^a of the shaft 10 and mounted to rotate independ- 130

ently thereof. The sleeve is equipped with resetting-cams 45, similar to the cams 31, and the wheels *a* are equipped with locking-paws 33, precisely as heretofore described.

5 At the outer end of the sleeve 44 is fixed a pinion 30^a, similar to the pinion 30 and arranged to be operated by a second resetting-lever 27^a, constructed, mounted, and operated precisely like the lever 27. The locking-levers 23, which serve the wheels *a*, are independent of the other group of levers serving the wheels *b* and *c*, but have the same interdependent relation by means of lugs 26^a and are likewise retracted by a retractor 40^a, operated by the resetting-lever 27^a.

The described mechanism for retracting the transfer-levers of the wheels *a* is duplicated at the left-hand side of the register. In other words, the transfer and locking-levers serving the wheels *b* and *c* and said wheels themselves are operated in the operation of resetting by the manipulation of the lever 27 and its associated parts, while precisely similar but independent mechanism, including 25 the separate lever 27^a, is provided for effecting the resetting of the wheels *a*. It should be stated at this point that neither the carrying mechanism, the wheel-locking mechanism, nor the resetting mechanism considered 30 specifically constitute any part of my present invention, the advantages of which reside in providing in a machine of this class a plurality of separate computing devices, totalizers, or registers in a single casing with the greatest possible economy of space in order to facilitate the totalizing of comparatively narrow directly-adjoining columns.

The invention also resides in mounting these several groups or sets of wheels upon a 40 common support which is adjustable to accommodate the particular location of the columns on a work-sheet; and a still further feature of the invention resides in the relative arrangement of the resetting mechanisms 45 whereby certain of the sets of wheels or registers while capable of computing different totals may be simultaneously reset independently of another group of wheels, which may be reset when desired.

50 It will now be observed by reference more particularly to Fig. 6 that by arranging all of the wheels in a single series of equidistant units eighteen registering-wheels, for instance, may be appropriated for the totalizing of three directly-adjoining columns, each of which is of only sufficient width to accommodate five denominational positions. For instance, in the example given the wheels and columns being proportioned with reference 55 to the ordinary ten-to-the-inch spacing of the type-writing machine the highest number capable of being printed in any one of the three columns is hundreds of dollars, while the set of wheels or register serving the column has a capacity for thousands of dollars.

Thus the two numbers shown in the column to the left each occupy five denominational positions, which is the full capacity of the column, while the total occupies six denominational positions, which is beyond the capacity of the column, but is within the capacity of the totalizer. This is made possible by utilizing for a number-wheel the space which necessarily separates adjacent numbers in adjoining columns instead of having this space occupied by the adjacent walls of two casings.

It is thought that from the foregoing the construction, operation, and advantages of my machine will be clearly understood; but while the present embodiment of the invention appears at this time to be preferable I desire to reserve the right to effect such changes, modifications, and variations thereof as may come fairly within the scope of the protection prayed.

What I claim is—

1. As a means for recording and totalizing adjoining parallel columns of numbers, a traveling recording mechanism, a master means movable therewith and operated thereby, and a computing device including a casing, several independent groups or sets of number-wheels mounted in the casing and arranged to be operated by the master means, and separate resetting mechanisms, one of said mechanisms being arranged to reset a single group of wheels and another of said mechanisms being arranged to simultaneously reset a plurality of groups of wheels.

2. The combination with a type-writing machine including the printing devices and keys, of a computing device including a casing, a continuous series of aligned number-wheels mounted in the casing, carrying mechanisms forming the series of wheels into independent groups or sets, the wheels of each group or set having co-operative relation, a master means operated by the keys of the type-writer to rotate the number-wheels, and separate resetting mechanisms including operating members located beyond the opposite ends of the series of wheels.

3. The combination with a type-writing machine including the printing devices and keys, of a computing device including a casing, a continuous series of aligned number-wheels mounted in the casing, carrying mechanisms forming the series of wheels into independent groups or sets, the wheels of each group or set having co-operative relation, a master means operated by the keys of the type-writer to rotate the number-wheels, and separate resetting mechanisms one of which is common to a plurality of groups or sets of number-wheels.

4. The combination with a type-writing machine including a frame, a laterally-movable carriage, and printing devices and keys movable with the carriage, of a computing

- device including a casing, several independent groups or sets of number-wheels mounted in the casing, the wheels of each set being cooperatively related, a master means operated by the type-writer keys to rotate the number-wheels, and separate independent resetting mechanisms for different sets or groups of wheels, one of said mechanisms being common to a plurality of groups or sets. 5
5. The combination with a type-writing machine including a frame, a laterally-movable carriage, and printing devices and keys movable with the carriage, of a computing device including a casing, several independent groups or sets of number-wheels mounted in the casing, the wheels of each set being cooperatively related, a master means operated by the type-writer keys to rotate the number-wheels, a wheel-resetting mechanism located at one side of the computing-device casing and arranged to effect the simultaneous resetting of a plurality of groups or sets of number-wheels, and a second resetting mechanism located at the opposite side of the casing and arranged to effect the resetting of a single group or set of wheels. 10
6. The combination with recording mechanism and operating-keys therefor, of a computing device including a shaft, a group or set of number-wheels mounted on the shaft, a sleeve carried by the shaft and rotatable independently thereof, a second group or set of number-wheels mounted on the sleeve, key-operated master means for operating the number-wheels, and wheel-resetting mechanisms, one including means for rotating the shaft and the other including means for rotating the sleeve. 15
7. The combination with recording mechanism and operating-keys therefor, of a computing device including a casing, a shaft extending across the casing and having a reduced portion, a sleeve rotatable on the reduced portion of the shaft, a plurality of independent groups or sets of number-wheels mounted on the shaft, another group or set of number-wheels mounted on the sleeve, key-operated means for rotating the number-wheels, a wheel-resetting mechanism including means for rotating the shaft to simultaneously reset the groups or sets of number-wheels mounted thereon, and a second resetting means for rotating the sleeve to reset the number-wheels carried by the latter. 20
8. The combination with recording mechanism and a master means operated thereby, of a computing device operated by the master means and including several independent groups or sets of number-wheels, locking means common to the wheels of said sets or groups, wheel-resetting means, and means operated by the resetting means for simultaneously unlocking the locked wheels of said groups or sets. 25
9. The combination with recording mechanism and a master means operated thereby, of a computing device operated by the master means and including a plurality of independent groups or sets of number-wheels, locking means for the wheels of said sets or groups, and resetting means common to a plurality of groups or sets of wheels and arranged to effect the unlocking of the wheels prior to the resetting thereof. 30
10. The combination with recording mechanism and a master means operated thereby, of a computing device including several independent groups or sets of wheels, locking means for the wheels of each group or set, and a plurality of resetting mechanisms, one of said mechanisms being common to a plurality of groups or sets of wheels and arranged to unlock said wheels prior to the resetting thereof and the other resetting mechanism being arranged to operate a single group or set of number-wheels and to unlock the same. 35
11. The combination with a flat platen, of a type-writing machine mounted to travel thereover and including a machine-frame, a carriage movable on the frame, printing mechanism movable with the carriage, and keys for operating the printing mechanism, a guide-bar carried by the machine-frame, a computing device adjustable on said guide-bar and including several independent groups or sets of cooperatively-related number-wheels, and a master means mounted on the carriage and operated by the keys to actuate the number-wheels of the computing device. 40
- In testimony that I claim the foregoing as my own I have hereto affixed my signature in the presence of two witnesses.
- CHARLES FREDERICK LAGANKE.
